UNITED STATES PATENT OFFICE.

JAMES WILSON BARNES, OF BEAVERTON, OREGON.

FEED-TROUGH.

SPECIFICATION forming part of Letters Patent No. 705,896, dated July 29, 1902.

Application filed April 9, 1902, Serial No. 102,066. (No model.)

To all whom it may concern:

Be it known that I, JAMES WILSON BARNES, of Beaverton, in the county of Washington and State of Oregon, have invented a new and useful Improvement in Feed-Troughs, of which the following is a specification.

My invention is in the nature of an improved feed-trough designed more especially for feeding hogs. Its object is to promote cleanliness and secure better sanitation by protecting the food from being soiled by the dirt of the hogs' feet, to enable the small hogs to feed equally without being displaced by the large ones, to keep the hogs from feeding until the food is all properly placed in the trough, and to protect the clothing of the person feeding from being soiled by the splashing and crowding of the hogs.

It consists in the peculiar construction and arrangement of a rotary adjustable trough and rotary adjustable guard-board and means for locking them in their two positions, as will be hereinafter fully described with reference to the accompanying drawings, in

which—

Figure 1 is a front view; Fig. 2, a back view; Fig. 3, a vertical transverse section showing the position of parts when the hogs are feeding, and Fig. 4 a similar view showing the position of parts when the food is being deposited in the trough.

In the drawings, 14 is a platform on which the hogs stand while feeding. This platform is mounted on end sills 13 13, to which are also secured the upright end frames 11 11. These end frames are connected on the side upon which the hogs feed by a cross-bar 24.

L is the trough, which extends from one end frame 11 to the other and is pivotally supported therein by removable pins or trunnions 7 7 at the center of its ends, so as to have a half-rotation from the position shown in Fig. 3 to the dotted position shown in Fig. 4. When in the position shown in Fig. 3, the front edge of the trough rests against and is stopped by the front board 24 in position for the hogs to feed, and when turned to the dotted position shown in Fig. 4 the trough is made to discharge its contents and may be washed out clean. The trough is divided transversely into compartments by bars 8, which give space for each hog to feed with-

out being pushed aside by his neighbor. These bars extend only across the top part of the trough, so that the food may flow from end 55 to end of the trough and be distributed along its length. Said bars are rigidly connected to both sides of the trough and serve also to brace the same. At one or both ends of the trough one of the compartments 9 is separated from the others by a partition extending all the way to the bottom. This is to hold water.

Just above the trough there is arranged a guard-board 5, which is pivotally supported 65 at the middle of the ends on pins 21 in the end frames and is adapted to be turned about its horizontal axis, so as to open the trough to the hogs' side when feeding or cut off the trough from the hogs and permit the person 70 feeding or cleaning the trough to have uninterrupted control of the same, as shown in Fig. 4.

For holding the trough and guard-board in their two positions the following devices are 75 employed: A top cross-bar 12 is connected to the tops of the two end frames 11 and near the middle has two blocks 23 23, between which is pivoted a gravity-latch 15, whose shouldered end hangs down past the cross-bar 12. On the back side of the trough there is rigidly fixed an upwardly - projecting notched arm 3, which both serves as a handle to turn the trough by and also a locking-arm with which there engages a spring-latch 4 on 80 the guard-board. When the trough is disposed in the position shown in Fig. 3 for feeding, the spring-latch 4 locks behind the notch of the arm 3 and holds the parts in this position, and when the trough and guard-board 85 are in the position shown in Fig. 4 then the guard-board is caught and held by the gravity-latch 15, so as to cut off access of the hogs to the trough, and the arm 3 then forms a handle for rotating the trough to clean it out 90 and restore it. The guard-board 5 in one position cuts off the hogs from the trough while the person is preparing the food and prevents the hogs from splashing or crowding into the food before it is fully prepared, and in the 95 other position the guard-board prevents the hogs from thrusting their heads beyond the trough.

I am aware that a feed-trough has been pro-

vided with a swinging guard-board arranged to pass from one side of the trough to the other, and I make no broad claim to this.

Having thus described my invention, what I claim as new, and desire to secure by Letters Patent, is—

1. A feed-trough comprising a trough hung upon pivots at the center of its ends so as to have a rotary adjustment, and a guard hung about pivots at the middle of its ends immediately above the trough, so as to be reversible, said trough and guard having locking devices coöperating with each other to hold the parts in their proper positions substantially as described.

2. A feed-trough, comprising a trough hung about centers at its ends, so as to have a rotary adjustment, and having also a projecting arm acting as a manipulating-handle and also as a locking device, and a guard hung about centers at its ends above the trough and having a spring-latch engaging the locking-arm of the trough substantially as described.

25 3. A feed-trough, comprising a trough hung

about centers at its ends so as to have a rotary adjustment and having also a projecting arm acting as a manipulating-handle and also as a locking device, a guard hung about centers at its ends above the trough and having a 30 spring-latch engaging the locking-arm of the trough, upright end frames with a cross-bar at the top, and a gravity-catch on said cross-bar adapted to engage and hold the guard substantially as described.

4. A feed-trough comprising a platform 14 with sills 13, 13; upright end frames 11, 11, mounted thereon and having cross-bar 12 at the top and lower cross-bar 24 at the bottom next to the platform, a trough hung on a horizontal axis between the end frames, and a guard - board also hung between the end frames on a horizontal axis, and locking devices for holding the trough and guard in two positions as described.
